US00D820046S

(12) United States Design Patent (10) Patent No.: US D820,046 S
(45) Date of Patent: * Jun. 12, 2018

(54) CONTAINER

(71) Applicant: YETI Coolers, LLC, Austin, TX (US)

(72) Inventors: Roy Joseph Seiders, Rollingwood, TX (US); Steve Charles Nichols, Austin, TX (US); Chris Nickolas Kaschner, Austin, TX (US)

(73) Assignee: YETI Coolers, LLC, Austin, TX (US)

() Term: 15 Years

(21) Appl. No.: 29/563,754

(22) Filed: May 6, 2016

(51) LOC (11) Cl. 07-01

(52) U.S. Cl.

USPC D7/533; D7/536; D7/532

(58) Field of Classification Search

(74) Attorney, Agent, or Firm — Banner & Witcoff, Ltd.

(57) CLAIM

The ornamental design for a container, as shown and described.

DESCRIPTION

FIG. 1 is a top, front, right side perspective view of a first embodiment of a container showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, right side perspective view of a second embodiment of a container;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines in the drawing depict portions of the container that form no part of the claimed design.

1 Claim, 14 Drawing Sheets
